(57) **CLAIM**

The ornamental design for a headset, as shown and described.

DESCRIPTION

FIG. 1 is a front perspective view of a headset showing our new design;

FIG. 2 is a rear perspective view of the headset in FIG. 1.

FIG. 3 is a front elevation view of the headset in FIG. 1.

FIG. 4 is a rear elevation view of the headset in FIG. 1.

FIG. 5 is a left side elevation view of the headset in FIG. 1.

FIG. 6 is a right side elevation view of the headset in FIG. 1.

FIG. 7 is a top plan view of the headset in FIG. 1; and,

FIG. 8 is a bottom plan view of the headset in FIG. 1.

The broken lines in the drawings are employed to show unclaimed portions of the headset, and form no part of the claimed design.

1 Claim, 8 Drawing Sheets
